(57) **CLAIM**

The ornamental design for a compass with short base and cover, as shown and described.

DESCRIPTION

FIG. 1 is a top view of a compass with a short base and a closed cover according to my new ornamental design, wherein the cover is shown in a closed position, and the base is transparent and the cover is opaque;

FIG. 2 is a bottom view of the compass with short base and cover shown in FIG. 1, wherein the bottom view remains the same when the cover is opened and closed;

FIG. 3 is a front view of the compass with short base and the closed cover shown in FIG. 1;

FIG. 4 is a rear view of the compass with short base and the closed cover shown in FIG. 1;

FIG. 5 is a right side view of the compass with short base and the closed cover shown in FIG. 1;

FIG. 6 is a left side view of the compass with short base and the closed cover shown in FIG. 1;

FIG. 7 is a perspective view of the top, right side and rear of the compass with the short transparent base and the closed opaque cover shown in FIG. 1;

FIG. 8 is a top view of the compass with the long base and a cover as shown in FIG. 1, wherein the cover is shown in an open position;

FIG. 9 is a front view of the compass with the long base and the open cover shown in FIG. 8;

FIG. 10 is a rear view of the compass with the long base and the open cover shown in FIG. 8, wherein an inside surface of the cover is a reflective mirror conforming generally to a top face of the compass portion shown in FIG. 14;

FIG. 11 is a right side view of the compass with the long base and the open cover shown in FIG. 8;

FIG. 12 is a left side view of the compass with the long base and the open cover shown in FIG. 8;

FIG. 13 a perspective view of the top, right side and rear of the compass with the long base and open cover shown in FIG. 8; and,

FIG. 14 is a perspective view of the top and side of the compass portion of the compass with the long base and cover shown in FIGS. 1 and 8.
